UNITED STATES PATENT OFFICE

JEANNE F. GREIG, OF LONDON, ENGLAND, ASSIGNOR TO THE CHARNAX PATENT CORSET COMPANY LIMITED, OF LONDON, ENGLAND

DESIGN FOR A CORSET

Application filed December 17, 1931. Serial No. 42,114. Term of patent 14 years.

To all whom it may concern:

Be it known that I, JEANNE F. GREIG, a subject of the King of Great Britain, residing at 66 Gloucester Place, London, England, have invented a new, original, and ornamental Design for Corsets, of which the following is a specification, reference being had to the accompanying drawings, forming part thereof.

Figure 1 is a front view of a corset showing my new design, and

Figure 2 is a back view of a corset showing my new design.

I claim:

The ornamental design for a corset, as shown.

JEANNE F. GREIG.
